ABSTRACT

In order to indicate a function status which can be one of three states, upon detecting a first state, a bicolor LED is lighted with a first color; upon detecting a second state, the LED is lighted with a second color; and upon detecting a third state, the LED is alternately lighted with said first and said second colors at a sufficiently high rate to cause the color of the LED to appear as a third color.

TRI-STATE FUNCTION INDICATOR

RELATED APPLICATIONS

This application is related to the following applications filed on even date herewith, the disclosure of which is hereby incorporated by reference. These applications contain, at least in part, common disclosure regarding an embodiment of a peripheral repeater box. Each, however, contains claims to a different invention.

- Peripheral Repeater Box Ser. No. 085,097
- D.C. Power Monitor Ser. No. 085,095
- Method of Changing Baud Rates Ser. No. 085,084
- System Permitting Peripheral
- Interchangeability Ser. No. 085,105
- Communications Protocol Ser. No. 085,096
- Method of Packetizing Data Ser. No. 085,098

BACKGROUND OF THE INVENTION

This invention relates to computer systems in general and more particularly, to a tri-state function indicator particularly useful in a computer system.

In large computer systems, and particularly in systems which provide graphics displays, a plurality of different types of peripheral devices for providing input to the computer system are provided. For example, a single system may have as inputs a keyboard, a mouse, a tablet, a light pen, dial boxes, switch boxes and so forth. In a system with a plurality of such peripherals it is advantageous to have a device which can collect inputs from each of these peripherals and then retransmit the various inputs over a single line to the computer system. Such a device is referred to herein as a peripheral repeater box in that it acts as a repeater for each of the individual peripherals.

Preferably, a peripheral repeater box of this nature, which will include its own processor, will be capable of running various levels of self test. Some indication should be given of the status of the peripheral repeater box, i.e. whether it is in a test mode or in an operating mode. Similar requirements for indicating status are found in other systems, particularly computer systems.

SUMMARY OF THE INVENTION

The present invention provides such a function indicator. The function indicator is disclosed in the setting of a peripheral repeater box. It will be recognized, however, that the tri-state function indicator of the present invention is equally applicable in many other settings.

The Peripheral Repeater box (PR Box) of the present invention is, first of all, used to allow the peripherals to be powered at the Monitor site. The PR box collects the various peripheral signals using, a conventional RS-232-C or RS-423 connection, from seven peripheral channels, which are then packetized and sent to a host, e.g. a computer and/or graphics control processor, using RS-232-C signals. Transmissions to the peripherals are handled in a like manner from the host, i.e., receiving packets from the host, unpacking the data and channeling data to an appropriate peripheral serial line unit (SLU).

The peripheral repeater box of the present invention is particularly suited for use in a graphics system of the type disclosed in copending Applications Ser. Nos. 084,930 and 085,081, entitled Console Emulation For A Graphics Workstation and High Performance Graphics

Workstation, filed on even date herewith, the disclosure of which is hereby incorporated by reference.

In addition to providing a multiplexing/data concentration function for the peripherals, the PR box also implements a self-test check on its own logic (performed on power-up and on command request) and an external loopback function for manufacturing testing. The manufacturing test mode, which is an extended version of self-test, operates when the manufacturing jumper is detected in circuit. When in this mode the self-tests run continuously unless an error is detected at which time it will loop on the failing test. This mode requires a special loopback module.

A function LED and a group of 8 diagnostic LEDs 15 are located on the back panel of the PR Box. The function LED is utilized to indicate which state the PR box is in, i.e., the function being performed. The current error status, if any, is reflected in the diagnostic LEDs. The diagnostic LEDs are also available to the host to provide additional status information in the case where 20 the graphics system is unable to display messages on its video display. A command is available to the system by which to write an error code to the diagnostic display. In accordance with the present invention, the function LED is a tricolor LED permitting indication of one of 25 three states of conditions of operation.

BRIEF DESCRIPTION OF THE DRAWINGS

FIG. 1 is a block diagram of a computer system in which the PR box of the present invention may be used.

FIG. 2 is a basic block diagram of the PR box of the present invention.

FIG. 3 is a schematic diagram of the function indicator LED of the present invention.

FIGS. 4A-C a flow diagram of the firmware running in the PR box of the present invention.

DETAILED DESCRIPTION

System Overview

FIG. 1 is a block diagram of a computer system showing where the peripheral repeater box of the present invention fits into the system. The illustrated system is a graphics system. However, the present invention is applicable to other computer systems. Thus, there is illustrated a monitor 11 which receives video input from a RGB coax 13 which is coupled to computing apparatus 14 which does the graphic computations. Included in apparatus 14, as illustrated, is a graphics engine or graphics processor 15, a main computer 17, e.g. a Vax 8250 system, and a computer 19 acting as a control processor, which may be a Microvax computer. Computer 17 is host to computer 19 and computer 19 is host to the PR box 21 described below. Thus, hereinafter, where reference is made to a host, the reference is to computer 19. The operation of this part of the system is more fully described in Applications Ser. Nos. 084,930 and 085,081, entitled Console Emulation For A Graphics Workstation and High Performance Graphics Workstation, filed on even date herewith. The peripheral repeater box 21 is illustrated in FIG. 1 along with the various peripherals which may be plugged into it. These include a keyboard 23, a mouse 25, a tablet 27, knobs 29, i.e. a dial box, buttons 31, a spare RS232 channel 33 and a spare keyboard input 35.

The peripheral repeater box is a self-contained microprocessor system which, in the illustrated embodiment, is located underneath the monitor. It is responsible for

handling information flowing between the host and peripheral devices. This is a free running sub-system that performs a self-check of its own internal status at power up. After completing this task it initializes itself and continuously scans for activity from the host or peripherals.

Four peripheral channels (for keyboard 23, mouse 25, tablet 27 and knobs 29) and one command channel (for communications with the host) are provided to connect all the supported peripherals. In addition three spare channels for future expansion or special peripherals, e.g. the spare keyboard 35, button box 31, and spare 33 of FIG. 1 have been provided.

The sub-system is composed of a minimal system as shown in FIG. 2. Thus, there is illustrated an 8031 microprocessor CPU 41 which, in conventional fashion, has a associated with it a clock/reset unit 43 with a 12 mHz crystal oscillator. Coupled to the 8031 CPU is a conventional control decode block 45 which couples the CPU to a bus 47. Bus 47 couples the CPU to memory 49 which includes 16K of RAM 51 and 8K of ROM 53. The 8031 has no on chip ROM and insufficient on chip RAM. For this reason, the 8031 is used in an expanded bus configuration utilizing three of the four available general purpose ports for address, data and control. These are coupled through block 45 to bus 47. Enabling the external addressing capability for the expanded bus configuration is accomplished by grounding (through a jumper) the EA, external access, pin.

The low order address and data are multiplexed on the 8031, the address is latched during address time with a 74LS373 Octal latch strobed via the ALE (address latch enable) signal output from the 8031.

Bus 47 is also connected to a diagnostic register 55. Diagnostic register provides an output to a display 57 comprising 8 LEDs. Also coupled to bus 47 is a function register 59 which provides its output to a tricolor LED 61 to be described in more detail below. Also shown in FIG. 2 is the DC power monitor 63 which provides its output to a bicolor LED 64 to indicate under or over voltage conditions as explained in detail below.

Bus 47 also connects to Serial Line Units (SLU) 0-7 along with a modem control contained in block 62. Block 62 is what is known as an octal asynchronous receiver/transmitter or Octalart. Such a device is manufactured by Digital Equipment Corporation of Maynard, MA. as a DC 349. Basically, the Octalart comprises eight identical communication channels (eight UARTS, in effect) and two registers which provide summary information on the collective modem control signals and the interrupting channel definition for interrupts. Serial line units 0-6 are coupled to the seven peripherals indicated in FIG. 1. SLU 7 is the host link shown in FIG. 1. The outputs of the SLUs are coupled through transceivers 69, the outputs of which in turn are connected to a distribution panel 71 into which the various connectors are plugged. Block 69 includes EIA Line drivers, 9636 type, operating off a bipolar supply of +/−12 volts which translate the signals from TTL levels to a bipolar RS-232-C compatible signal level of approximately +/−10 volts.

The host channel (SLU 7), keyboard channel and spare channel do not have device detection capability. The other five channels have an input line that is connected to the DCD (Data Carrier Detect) pin of the corresponding SLU of the Octalart 62. When the pin is at the channel connector side is grounded the input side

of the Octalart is high indicating that a device is present on that channel.

5 A data set change summary register in block 62 will cause an interrupt if the status of one of these pins changes, i.e. high to low, or low to high level change. This indicates a device being added or removed after the system has entered operating mode. On power up the 8031 reads this register to determine which devices 10 that have this capability are connected and enter this information into a configuration byte (a storage area in software) and is sent to the host as part of the self test report. This capability permits knowing which peripherals are connected to which ports and thus allows 15 interchangeability of peripherals. The PR box, each time a peripheral is plugged in or unplugged, sends a message to the host allowing it to interrogate a peripheral and update a table which it maintains.

In the free running operational mode the PR box 20 accepts data packets from the host through SLU 7 and verifies the integrity of that data. If the data is good then the PR box sends an ACK to the host, strips out the data or command from the packet and channels it to the designated peripheral through its associated SLU. If the data is bad, i.e. checksum error, the PR box sends a 25 NAK to the host to request a re-transmission and throws away the packet it had received. These communications are described in detail below in connection with FIGS. 5C through 11C.

The PR box can also receive commands to test itself 30 and report status/configuration to change the diagnostic LEDs and to change baud rates while in operational mode.

Self-test mode verifies the integrity of the microprocessor sub-system. After termination of the internal 35 loopback of the Octalart, the sub-system will re-initialize itself and return to operational mode. Self-test is entered on power-up or by receipt of an executed self-test command from the host. This will check the functionality of the PR box logic.

An internal loopback sub-test is provided in the self-test, allowing the system to verify the integrity of the 40 PR box logic under software control. While the self test is in operation there is no logical connection between the host and the PR box. This is true only during self-test. There is no effect on the peripherals when the PR 45 box is running the internal loopback portion of self-test because no data is output at the transmit pins of the UART lines in Octalart 67. Additionally data coming in from the peripherals will have no effect on the PR box 50 during loopback test since all data at the UART receive pins of Octalart 67 is ignored.

External loopback testing may be performed on an 55 individual peripheral channel using the appropriate loopback on the channel to be tested. This is done from the host firmware. The peripheral repeater is transparent from this operation. This is the testing, explained further below which allows peripheral interchangeability.

A manufacturing test mode is provided by a jumper 60 in the host channel loopback connector. This jumper is sensed on an 8031 on the power-up. In this mode the module runs all tests (as in self-test) on all channels and a device present test, and an external peripheral channel loopback test, continually. Loop on error functionality 65 has been implemented to aid in repair.

The eight bit diagnostic register 55 with eight LEDs 57 attached provides the PR box status and some system status, (assuming some basic functionality of the main

system). This register is used by the PR box to indicate its dynamic status during self-test or manufacturing test, to indicate, on entry to operational mode, any soft or hard error that may have occurred. The MSB, (bit 7) is used to indicate that a PR box error has occurred, bit 6 is used to indicate that a system error is displayed. If bit 6 is lit then the error code displayed is the system error, regardless of bit 7. This leaves 6 bits for providing encoded error responses.

The Function Monitor

As shown in FIG. 2, a tristate LED 61 is connected to the output of two bit function register 59. This is used to give visual indication of what mode or function the PR box is performing at that time.

LED Indication	Description
Yellow	Self-test mode being executed
Red	Manufacturing test being performed
Green	Operational mode active

The circuit for driving, function indicator LED 61, is illustrated in FIG. 3. Register 59 indicates which function the PR box is currently performing, i.e. self-test, operation or manufacturing modes. It is a two bit register made up of a 74LS74 dual D type flip flop using 2 bits of a 74LS244 driver for read back. Each flip flop in the register has both a noninverted and an inverted output. Thus, the bit 0 flip flop provides a mode 00L signal and a mode 00H signal and the bit 1 flip flop a mode 01L signal and a mode 01H signal. The read back function has been added so that correct operation of the register hardware, exclusive of the LED can be checked automatically by the self-test software. The function is indicated by a single bicolor LED 61 operated in a tristate mode to produce three discrete colors.

A clock signal is provided as an input to a four-bit binary counter 201 to provide a divide by 16 clock output on output line 203. The output on line 203 is provided as an input to a second four-bit binary counter 205 where the signal is again divided by 16 to obtain a clock of approximately 19 KHz. Both counters 201 and 205 are cleared by a power up signal on line 207.

Signals mode 00 low and mode 01 low from function register 59 are provided as inputs to a Nand gate 209. Mode 00 corresponds to bit 1 and mode 01 to bit 2 of two bit register 59. Similarly, signals mode 01 low and mode 00 high are provided into a Nand gate 211. Mode 01 high is provided as an input to a Nand gate 213 which has as its second input the output of the binary counter 205. The output of this gate is the clock input to a D-type flip-flop 215. The "1" output of flip-flop 215 on line 217 is coupled as one input to Nand gate 219. The "0" output on line 220 is coupled as one input to Nand gate 221. These gate comprise a 75452 dual peripheral driver. The second input to Nand gates 219 and 221 is a three volt signal. The output of Nand gate 219 on line 223 is coupled to the red cathode of a bicolor LED 225. Similarly, the output on line 227 is coupled to its green cathode. Each of the cathodes is powered by plus 5 volts through resistors 229 and 231 respectively. These are open collector devices and thus the power for the LED is provided through the two resistors 229 and 231 tailored to operate the two LED sections at the same optical luminescence. Note that the heavier peripheral driver is required since, regardless of which

LED is enabled, current flows through both resistors at all times.

In operation, if both modes 00 and mode 01 are low, the output of gate 209 will be a logic "1" and the flip-flop 215 will be preset thereby providing an output on line 217 which is coupled through Nand gate 219 to energize the red cathode of diode 225. If mode 01 is low and mode 00 is high an output from gate 211 will cause flip-flop 215 to be cleared and an output on line 221 will result causing the green cathode to be energized. If mode 01 is high then the clocking signal will be provided at the output of gate 213. Because mode 01 is high, neither Nand gate 209 or 211 will provide an output to cause the flip-flop 215 to be preset or cleared. 10 In a D-type flip-flop, the clock signal will cause whatever is at the D input to be transferred to the "1" output. The D-input is tied to the "0" output on line 221. Thus, if, for example, line 221 is "0" then the "0" will be transferred to the "1" output on line 217 at which point line 221 will come to a logic "1" level. On the next clock cycle this logic "1" will be transferred to the "1" output on line 217. As a result, the red and green cathodes will be alternately energized and, because of the clock rate, it will appear to the observer to be the color yellow.

PE Box Operation Overview

The PR box ROM 53 contains self-test and operational firmware. This firmware is contained in 4K bytes of ROM, though there is 8K bytes reserved for it. A listing of the firmware is set out in Appendix A. A flow diagram for the firmware is set out in FIGS. 4 and 4-A-C.

On power-up indicated by block 301, the on board diagnostics will have control of the PR box as indicated in block 303. The diagnostics will perform tests on the PR box logic and do an external loopback and test if pin 7 on the 8031 port 1 is grounded (signifying manufacturing mode). In manufacturing mode the diagnostics will loop forever via loop 305 and not go into operational mode. This is done via detection of the loopback connector (pin 7) on power up. If an error is encountered during manufacturing mode, the diagnostics will loop forever on the test that encountered the error.

Registers 55 and 59 with LEDs 57 and 61 (see FIG. 2) attached can be viewed from the outside of the system box. Diagnostic register 55 as noted above is 8 bits wide with Red LEDs. These LEDs report errors for the PR box and/or the system. As also described, the function register 59 is two bits wide with a single red/yellow/-green LED. When in manufacturing mode, the function LED is red as indicated in block 303. On power-up, during other than manufacturing mode, the function LED will be yellow. In operational mode it will be green.

The various tests performed on power up are indicated by blocks 307-314. If in manufacturing mode, as checked in block 315 of FIG. 5B, the test of blocks 316 and 317 are also performed before entering block 318 to loop 305.

If, on power up, the PR box has an error that will make the PR system unusable, i.e. interrupt, 8031 errors, the function LED will stay yellow, an attempt to put the error code in the diagnostic register will be made, and the PR box will not go into operational mode.

If there are no errors or errors that will not make the system unuseable, and the system is not in manufacturing mode, path 320 will be followed to block 401 of FIG. 4C and the function LED will turn green and wait

for the host to ACK/NAK, the diagnostic report to establish the link between the host and the PR box. If the link is never established, the error code for NO host is placed into the diagnostic LEDs, and the PR box will go into operational mode. If the communications link is later established, the error code will be cleared.

If there are soft errors (diagnostic register or function register) the PR box will go into operational mode of FIG. 4C and carryout the background process. However, any LED indication may be incorrect. Except for a dead system, i.e. 8031 failures, the PR box will attempt to go operational mode, displaying, if possible, the point at which it failed the self-test, (test number).

After the power-up diagnostics have been completed, control is passed to the operational firmware. In this mode, the firmware will keep the link between the host and the PR box active, and mux/demux commands/data between the peripherals and the host. This operation is described in detail below.

The diagnostics/operating system of this system are ROM based and run out of the 8031 microprocessor. The PR box firmware is compatible with the existing peripherals, and adheres to a communications protocol developed for the host PR box link discussed below.

The diagnostics are the first part of the firmware to run on power-up of the PR box. The diagnostics leave the system in a known state before passing control to the operating firmware. Upon completion of testing the PR box, the system RAM **51** is initialized, queues are cleared, the UARTs in Octalart **67** are set to the default speeds and data formats, the diagnostic and mode registers **55** and **57** are set with the appropriate values, and a system status area is set up that contains the status of the PR box.

Once the diagnostics are complete, the diagnostic report is sent to the host, and the PR box goes into operational mode. If there are no other messages to send, the PR box will wait 10 seconds for an ACK-/NAK before placing an error code for "No communications link" into the diagnostic register 55. An ACK-/NAK timer is provided for all other packets and times out at 20 mSec. Once operational, the UARTS are enabled to allow communications between the peripherals and the host. A keep-alive timer is also enabled in order to keep the host link active.

SUBTTL BACKGROUND_LOOP

PAGE

NAME: BACKGROUND_LOOP

DESCRIPTION: This module contains the background routines for the operation of the PR Box. It will scan the queues to see if they are empty, and take the appropriate action if they are not.

Input: Receive and Transmit queues, and their appropriate pointers.

;

BACKGROUND LOOP:

```

        MOV      R7, #ZERO           ; Initialize R7 to point at channel 0
        MOV      R0, #REAR_RX_QUE_PTR ; Initialize R0 to point at the rear rec
eive que poi
        MOV      R1, #FRONT_RX_QUE_PTR ; Initialize R0 to point at the front re
ceive que po

```

```
10$:    MOV      A, @R1          ; Place the current queue's front pointe
        r in the acc
        XRL      A, @R0          ; Is it equal with the rear??
        JZ      20$              ; Yes, nothing is in the queue
```

ACALL BUFFER MOVE : NO. something is in the queue

```
20$:    INC    R7          ; Look at the next channel
        INC    R0          ; Point to the next REAR pointer
        INC    R1          ; Point to the next FRONT pointer
        CJNE   R7, #CMD_PORT + 1, 10$ ; Are we past the last virtual channel?
```

NO, see II C

; See if there is anything in the transmitter queues

```
        MOV      R7,#ZERO          ; Initialize R7 to point at channel 0
        MOV      R0,#REAR_TX_QUE_PTR ; Initialize R0 to point at the rear tra
nsmit que po
```

69

```

SJMP    END_XFER

30$:    MOV     A, @R1          ; Get the pointer to the front of the queue
        ADD     A, #NEXT_PTR      ; Point to the first buffer address in the queue
        MOV     R0, A            ; Put it in R0 to use as an external fetch
        MOVX   A, @R0          ; Get the received buffer lower address
        MOV    DPL, A          ; And save it in DPL
        INC    R0              ; Point to the high byte of the address
        MOVX   A, @R0          ; Do the same for the upper byte
        MOV    DPH, A          ; And save it in DPH
        MOV    A, #HOST_PORT    ; Port number to check the Tx queue
        SJMP   10$              ; Now, make sure that the HOST PORT Tx buffer isn't full

20$:    POP    ACC
        MCV    R1, A          ; Restore R1
        POP    ACC
        MOV    R0, A          ; Restore R0
END_XFER:
        RET

```

SUBTTL ENABLE_TX
PAGE

NAME: ENABLE_TX

DESCRIPTION: This routine will set the transmitter enable bit in the command register of the DC349 for the channel specified in Register 7.

INPUT: R7 = Channel number

OUTPUT: Tx Interrupt enable bit will be set in the appropriate DC349 command register.

ENABLE TX:

```

    - PUSH    ACC
    CALL    READ_COMMAND      ; Read the command reg. for this channel
it
    ORL     A,#TXIE_BIT       ; Set the transmitter interrupt enable b
    CALL    WRITE_COMMAND     ; Write back the command reg.
    POP     ACC

```

SUBTTI. PUSH MSG

PAGE

TITLE: PUSH_MSG

DESCRIPTION: This subroutine pushes a buffer address from the front of a receive queue to the rear of a transmit queue.

INPUT: DPTR = Buffer address to transfer
A = Channel to transfer to (Tx or Rx_queue)
PUSH_RX_TX = 1 to transfer addr to Rx queue
= 0 to transfer addr to Tx queue

SUBTTL CHANAD

PAGE

```

;*
;*          NAME: CHANAD
;*
;* DESCRIPTION: This subroutine will take the number in R7, multiply it
;* to the by eight and add it to the data pointer. This
;* routine is used for getting the appropriate address
;* for the current port on the octart.
;*
;* INPUT: Channel number in R7
;*        Base register address in the DPTR
;*
;* OUTPUT: Direct register address in DPTR
;*****

```

CHANAD:

```

PUSH ACC
MOV B,R7 ; Get channel being tested
MOV A,#REG_OFFSET ; Set up offset for mult.
MUL AB ; Compute offset
ADD A,DPL ; Add it in to address
MOV DPL,A ; Write it back to Data Ptr.
POP ACC
RET

```

SUBTTL CHANADR1

PAGE *

```

;*
;*          NAME: CHANADR1
;*
;*****

```

DESCRIPTION: This subroutine will take the number in R7, multiply it by eight and add it to REGISTER 1. This routine is used for getting the appropriate address for the current port on the octart.

INPUT: Channel number in R7
Base register address in R1

OUTPUT: Direct register address in R1

CHANADR1:

```

PUSH ACC
MOV B,R7 ; Get channel being tested
MOV A,#REG_OFFSET ; Set up offset for mult.
MUL AB ; Compute offset
ADD A,R1 ; Add it in to address
MOV R1,A ; Write it back to register 1
POP ACC
RET

```

SUBTTL INC_BUF

PAGE

NAME: INC_BUF

DESCRIPTION: This subroutine will take the address in the DPTR and increment it by one. If it is past the 1K boundary for this channel, it will get reset to the beginning of the buffer.

INPUT: DPTR - Address of the buffer byte just filled
R7 - Channel number

OUTPUT: DPTR - DPTR + 1 mod 1K

REGISTERS DESTROYED: R5

INC_BUF:

```

PUSH ACC

INC DPTR ; Point to the next free byte in the buffer
MOV A,DPL
CJNE A,#ZERO,80$ ; Are we on a page boundary?? NO, exit.
; Yes, see if it's the beginning of the next buffer space
MOV A,DPH ; Get the addr. of the page
CJNE A,#HIGH CH1_BUFFER,10$ ; Beginning of channel 1's buffer?
MOV DPH,#HIGH CH0_BUFFER ; Yes, reset the buffer to the beginning
of channel
SJMP 80$ ; 80$ is the label for the beginning of channel 1's buffer

10$: CJNE A,#HIGH CH2_BUFFER,20$ ; Beginning of channel 2's buffer?

of channel
SJMP 80$ ; 80$ is the label for the beginning of channel 2's buffer

20$: CJNE A,#HIGH CH3_BUFFER,30$ ; Beginning of channel 3's buffer?
MOV DPH,#HIGH CH2_BUFFER ; Yes, reset the buffer to the beginning
of channel
SJMP 80$ ; 80$ is the label for the beginning of channel 3's buffer

30$: CJNE A,#HIGH CH4_BUFFER,40$ ; Beginning of channel 4's buffer?
MOV DPH,#HIGH CH3_BUFFER ; Yes, reset the buffer to the beginning
of channel
SJMP 80$ ; 80$ is the label for the beginning of channel 4's buffer

```

89

90

```

40$: CJNE A, #HIGH CH5 BUFFER, 50$ ; Beginning of channel 5's buffer?
      MOV DPH, #HIGH CH4_BUFFER ; Yes, reset the buffer to the beginning
      of channel
      SJMP 80$

50$: CJNE A, #HIGH CH6 BUFFER, 60$ ; Beginning of channel 6's buffer?
      MOV DPH, #HIGH CH5_BUFFER ; Yes, reset the buffer to the beginning
      of channel
      SJMP 80$

60$: CJNE A, #HIGH CH7 BUFFER, 70$ ; Beginning of channel 7's buffer?
      MOV DPH, #HIGH CH6_BUFFER ; Yes, reset the buffer to the beginning
      of channel
      SJMP 80$

70$: CJNE A, #END BUFFER SPACE, 80$ ; Are we at the end of the buffer space?
      MOV DPH, #HIGH CH7_BUFFER ; Yes, reset the buffer to the beginning
      of channel

80$: POP ACC ; Else return
      RET

```

```

; TITLE: TEST_BIT
;
; DESCRIPTION: This subroutine tests a byte passed in the ACC to see
; if a particular bit is set. The bit number is specified
; in R7. If it is set, the carry flag is set on return,
; otherwise it is cleared.
;
; INPUT: A = bit pattern to be tested.
; R7 = bit number to test for (from 0 to 7).
;
; OUTPUT: C set if bit is set, cleared otherwise.
;
; REGISTERS DESTROYED: A, R5
;
TEST_BIT:
    XCH    A,R7          ; A=bit number, save the acc
    MOV    R5,A          ; Get the bit number to test for into R5
    XCH    A,R7          ; Restore the accumulator and R7
    INC    R5          ; Normalize it (1 to 8)
;
1$:   RRC    A          ; Move the bit into the carry flag
    DJNZ   R5,1$          ; IF this is not the bit we are testing for THEN
loop again
;
    RET          ; ELSE return
;
SUBTTL SET BIT

```

```

; ORL    RX_IN_PROCESS,A ; SET THAT FLAG IN THE APPROPRIATE BYTE
; SET_BIT:
    MOV    A,R7
    MOV    R5,A          ; Get the bit number to test for
    INC    R5          ; Normalize it (1 to 8)
    MOV    A,#ZERO        ; Clear the accumulator
    SETB   C          ; Set the carry flag

1$:    RLC    A          ; Move the the carry flag into the bit
    DJNZ  R5,1$        ; IF this is not the bit we are setting THEN loop
p again

    RET          ; ELSE return

```

SUBTTL CLEAR_BIT

PAGE

```

; TITLE: CLEAR_BIT
;
; DESCRIPTION: This subroutine clears a bit in the ACC. The rest of
;               the ACC contains all ones. The bit number is specified
;               in R7.
;
; INPUT: ACC = byte in which to clear the bit.
;        R7 = bit number to clear (from 0 to 7).
;
; OUTPUT: ACC has the particular bit cleared.
;
; REGISTERS DESTROYED: ACC and R5
;
; USE:    CALL    CLEAR_BIT      ; R7 CONTAINS BIT TO BE CLEARED ALREADY
;         ANL    RX_IN_PROCESS,A ; CLEAR THAT FLAG IN THE APPROPRIATE BYT
E
;
; CLEAR_BIT:
    LCALL  SET_BIT          ; Set the appropriate bit
    XRL    A,#FILL          ; Then invert it to set all the other bits and clear the app

    RET          ; ELSE return

```

SUBTTL WRITE_COMMAND

PAGE

```

; TITLE: WRITE_COMMAND
;
; DESCRIPTION: This subroutine writes to the command register of
;               the DC349.
;
; INPUT: R7 - Channel number
;        ACC - Data to be written
;
; OUTPUT: COMMAND_REG(R7)=ACC
;
```

```

; WRITE_COMMAND:
    PUSH   DPL          ; Save the low byte of the data pointer

```

PAGE
;::::::::::::::::::::::::::::::::::::::::::::::::::::::::::::::::::
;
```

```

;      TITLE:  TIMER0_INT
;
```

```

;      DESCRIPTION: This routine will check the timer for each channel.
;                    If the timer for the channel is not zero, it will be
;                    decremented by one, and if zero, the message buffer for
;                    that channel will be terminated.  Though there is a
;                    byte reserved for channel 5 (spare port), it is not used.
;                    The counter for channel 5 is never set up in the uart
;                    interrupt routine (it's always zero) because the spare
;                    port will use one byte packets.  Channel seven also does
;                    not use the timer.
;
```

```

;      INPUT:  RX_TIME_OUT      ; Table of timers, one per channel
;
```

```

;      OUTPUT: RX_TIME_OUT(CHANNEL) = RX_TIME_OUT(CHANNEL)-1
;                  BUFFER IN CLOSED IF RX_TIME_OUT(CHANNEL)=0

PAGE

TITLE: UART SERVICE

DESCRIPTION: This Routine is the interrupt handler for the DC349. There are 4 parts to this interrupt handler, Rx and Tx for channels 0 thru 6, and Rx and Tx for channel 7. Channel 7 is handled separately because it is the host channel, and extra calculations are required on incoming and outgoing data on this channel (checksum, headers, ACK/NACK, etc.) Register bank 3 is used.

INPUT: None

OUTPUT: Data byte is read/written from/to the appropriate channel.
More specific data is given in each subroutine.

CHANGES: . BL2

9/11/86   Changed the subroutine name GET_BUF to INC_BUF.
| The old name was a misnomer.

9/12/86   Added the section of code for the Host port.

9/15/86   Created the subroutines QUE_BUFFER, READ_CHAR,
                  SAVE_BUF, and GET_BUF.

What is claimed is:

1. A method of indicating a function status which can be one of three function states, comprising upon detecting a first state, lighting a bicolor LED with a first color; upon detecting a second state, lighting the LED with a second color; and upon detecting a third state, alternately lighting said LED with said first and said second colors at a sufficiently high rate to cause the color of said LED to appear as a third color, said function states being indicated by a 2 bit binary code and further include:

generating a first signal when both of said binary bits are in a first binary state;
coupling said first signal to the preset input of a D type flip flop;
generating a second signal when a first of said binary signals is in a second state and a second of said binary signals is in said first state;
coupling said second signal to the clear input of the D type flip flop;
and generating a third signal when said second bit is in said second state;
providing a clock oscillator having a clock signal;
performing an And operation on said clock signal with said third signal;
providing said clock signal as the clock input to a flip flop;
coupling one of the outputs of said D type flip flop to its D input to alternate the outputs of the D type flip flop;
using said first signal to energize the first color of said LED;
using said second signal to energize the second color of said LED;
utilizing said third signal by triggering said D-type flip flop to generate an alternating signal to alternately energize said first and second colors in said LED.

2. A method according to claim 1 wherein:

30 said step of generating said first signal comprises Anding together signals representing the first state of said first and second bits; and
said step of generating said second signal comprising Anding together signals representing the second state of said first bit and the first state of said second bit.
35 3. Apparatus for indicating a function status which can be one of three function states wherein said function states are indicated by a two bit binary code, comprising:
40 means for detecting first, second and third states and providing as outputs first, second and third signals corresponding to said first, second and third states;
means for generating said first signal when both of said binary bits are in a first state;
means for generating said second signal when a first of said binary bits is in a second state and a second of said binary bits is in said first state;
means for generating said third signal when said second bit is in said second state;
a bicolor LED having a first cathode for a first color and a second cathode for a second color;
means for coupling said first signal to said first cathode;
means for coupling said second signal to said second cathode;
a clock oscillator generating clock pulses;
first means for Anding together said clock pulses with said third signal;
55 a D-type flip flop having first and second outputs and trigger input;
means for coupling said first signal to the preset input of said D type flip flop;
means for coupling said second signal to the clear input of said D type flip flop;
means for coupling one of the outputs of said D type flip flop to its D input to alternate the outputs of

137

said D-type flip flop;
 means for coupling the outputs of said D-type flip flop respectively to the first and second cathodes of said LED; and
 means for coupling the output of said first means for 5
 Anding together to the trigger input of said flip flop to thereby alternately energize said first and second cathodes at a sufficiently high rate to cause the color of said LED to appear as a third color.

10

138

4. Apparatus according to claim 3 wherein said means for generating said first signal comprise:
 means for Anding together signals representing the first state of said first and second bits; and
 said means for generating said third signal comprise
 means for Anding together a signal representing the second state of said first bit and the first state of said second bit.
